(57) **CLAIM**

The ornamental design for a sump plate, as shown and described.

DESCRIPTION

FIG. 1 is a side perspective view of a sump plate according to an embodiment of the invention;

FIG. 2 is a front view of the sump plate shown in FIG. 1;
FIG. 3 is a back view of the sump plate shown in FIG. 1;
FIG. 4 is a right side view of the sump plate shown in FIG. 1;

FIG. 5 is a left side view of the sump plate shown in FIG. 1;

FIG. 6 is a top view of the sump plate shown in FIG. 1; and,
FIG. 7 is a bottom view of the sump plate shown in FIG. 1.
The features shown in broken lines in the drawing depict the environmental subject matter and form no part of the claimed design.

1 Claim, 4 Drawing Sheets
